(57) **CLAIM**

I claim the ornamental design for a bottle cap with swing-out USB drive, as shown and described.

DESCRIPTION

FIG. 1 is a perspective view of the bottle cap with swing-out USB drive of the invention with the USB drive in the closed (in) position;

FIG. 2 is a perspective view thereof with the USB drive in the open (out) position;

FIG. 3 is a top plan view thereof with the USB drive in the closed (in) position;

FIG. 4 is a top plan view thereof with the USB drive in the open (out) position;

FIG. 5 is a bottom plan view thereof with the USB drive in the closed (in) position;

FIG. 6 is a bottom plan view thereof with the USB drive in the open (out) position;

FIG. 7 is a front elevation view thereof with the USB drive in the closed (in) position;

FIG. 8 is a front elevation view thereof with the USB drive in the open (out) position;

FIG. 9 is a side elevation view thereof with the USB drive in the closed (in) position; and,

FIG. 10 is a side elevation view thereof with the USB drive in the open (out) position.

The broken lines in the drawings show environmental structure and form no part of the claimed design.
